US00D817784S

(12) **United States Design Patent** (10) **Patent No.:** **US D817,784 S**
(45) **Date of Patent:** **** May 15, 2018**

(54) **FITNESS TRACKER WRIST BAND**

(71) Applicant: **STRIIV, INC.**, Redwood City, CA (US)

(72) Inventors: **Arthur Joseph Swenson**, Oakland, CA (US); **David Jong Wang**, Palo Alto, CA (US); **Mark A. Ross**, San Carlos, CA (US)

(73) Assignee: **STRIIV, INC.**, Redwood City, CA (US)

(**) Term: **15 Years**

(21) Appl. No.: **29/565,205**

(22) Filed: **May 18, 2016**

(51) LOC (11) Cl. **10-02**

(52) U.S. Cl.

USPC **D10/32**; D10/38; D10/70

(58) **Field of Classification Search**

USPC D10/30–33, 38, 46, 50–54, 57, 59, 65, D10/68, 70, 106.1, 106.6, 114.9, 116.1, D10/116.6, 119.4; D11/1, 3, 4, 22, 26, D11/46, 48, 53, 128, 138, 184; D14/94, D14/344; D24/167, 186, 187

(57) **CLAIM**

The ornamental design for a fitness tracker wrist band, as shown and described in the Figures.

DESCRIPTION

FIG. 1 is a perspective view of a fitness tracker wrist band according to the new design, the center fitness tracker shown in broken lines forms no part of the claimed design

FIG. 2 is a perspective view of the fitness tracker wrist band of FIG. 1 showing the new design;

FIG. 3 is a front elevation view of the fitness tracker wrist band of FIG. 2;

FIG. 4 is a rear elevation view of the fitness tracker wrist band of FIG. 2;

FIG. 5 is a left side elevation view of the fitness tracker wrist band of FIG. 2;

FIG. 6 is a right side elevation view of the fitness tracker wrist band of FIG. 2;

FIG. 7 is a top plan view of the fitness tracker wrist band of FIG. 2; and,

FIG. 8 is a bottom plan view of the fitness tracker wrist band of FIG. 2.

The broke lines in all the figure views show portions of the fitness tracker wrist band that form no part of the claimed design.

1 Claim, 8 Drawing Sheets
